UNITED STATES PATENT OFFICE.

WHEELER H. VIBBER, OF NEW LONDON, CONNECTICUT, ASSIGNOR OF ONE-HALF TO THE
GILLETTE-VIBBER CO. OF NEW LONDON, CONNECTICUT, A CORPORATION.

GROUNDING-CLAMP FOR ELECTRIC WIRES.

No. 905,773.

Specification of Letters Patent.

Patented Dec. 1, 1908.

Application filed April 11, 1908. Serial No. 426,563.

To all whom it may concern:

Be it known that I, WHEELER H. VIBBER, a citizen of the United States, residing at New London, in the county of New London 5 and State of Connecticut, have invented a new and useful Improvement in Grounding-Clamps for Electric Wires; and I do hereby declare the following, when taken in connection with the accompanying drawings and 10 the letters of reference marked thereon, to be a full, clear, and exact description of the same, and which said drawings constitute part of this specification, and represent, in—

Figure 1 a view in elevation of a grounding-clamp constructed in accordance with my invention and shown with a grounding-wire in place. Fig. 2 a view on the same scale of the clamp in side elevation. Fig. 3 a view of the clamp in vertical section on the 20 line *a*—*b* of Fig. 1. Fig. 4 a sectional view of the clamp on the line *c*—*d* of Fig. 1.

My invention relates to an improvement in grounding clamps for electric wires, the object being to provide a compact, convenient, durable and effective grounding clamp constructed with particular reference to cheapness and simplicity, to dispensing with the use of solder, and to bringing the grounding wire into direct contact with the pipe or 30 cable to which the clamp is applied so that the current will flow directly from the cable or pipe to the wire rather than through any intermediate parts.

With these ends in view my invention consists in a grounding clamp for electric wires, having certain details of construction as will be hereinafter described and pointed out in the claims.

In carrying out my invention as herein shown, I employ a strap preferably made of sheet-copper and bent to form a substantially circular body 2 approximately corresponding in diameter to the diameter of the pipe or cable to which the grounding 40 clamp is to be applied. The said strap is made long enough to form two arms 3, 4, projecting radially from the said body 2 and having alined perforations 5 for the reception of a binding screw 6 formed at one 45 end with a slotted head and provided with an ordinary nut 7. The said arms 3 and 4 are bent toward each other so as to make contact at their extreme ends when the clamp is in use, and the holes 5 are located so

close to the said body 2 that the polygonal 55 nut 7 engages with the body and is thereby prevented from turning, compelling the turning of the screw itself rather than the nut as is commonly done. If preferred the head of the screw may be made polygonal for the application of a wrench.

For the reception of the grounding-wire 8, that portion of the strap forming the body 2 is upset from the inside at a point opposite the said arms 3 and 4 so as to form a segmental inwardly opening groove or seat 9 running parallel with the length of the strap and therefore located in the plane of the clamp. This groove will substantially correspond in cross-sectional curvature to the 70 curvature of the grounding-wire 8 so that as the wire is forced out into this groove by the cable or pipe, it will make extended contact with the metal of the clamp. At the ends of the said groove the clamp is formed with 75 radial perforations 10 for the entrance of the grounding-wire 8 into the groove. One of these perforations 10 will answer all purposes though it is more convenient to have two as shown. The grounding-wire 8 by being introduced in this manner into the inside of the body of the clamp is brought not only into direct contact therewith, but also into direct contact with the pipe or cable by which it is forced into the said groove. This construction 80 therefore provides for the direct passage of the current from the wire or cable to the grounding-wire. The clamp is by preference formed with an opening 12 which may be used for soldering the wire to the clamp, if 85 desired though this is not essential.

I claim:

1. A grounding clamp having a wrought-metal strap bent to form a substantially circular body, and two radially projecting arms 95 which are perforated for the reception of a binding-screw, the said body being formed with an inwardly opening groove-like seat for the reception of the grounding wire, and with one or more lateral openings leading 100 into one or both ends of the said seat.

2. A grounding clamp having a wrought-metal strap bent to form a substantially circular body, and two radially projecting arms which are perforated for the reception of a 105 binding-screw, the said body being formed with an inwardly opening groove-like seat for the reception of the grounding wire, and

with two lateral openings respectively located at the ends of the said seat for the entrance and exit of the wire.

3. A grounding clamp having a wrought metal strap bent to form a substantially circular body, and two radially extending arms for the reception of a binding screw, the said body being formed with an inwardly opening groove-like seat for the reception of the grounding wire, with a lateral opening located between the ends of the said seat for

the reception of solder, and also with a lateral opening leading into one end of the seat.

In testimony whereof, I have signed this 15 specification in the presence of two subscribing witnesses.

WHEELER H. VIBBER.
